(57) **CLAIM**

The ornamental design for an intake manifold with an integrated PCV port, as shown and described.

DESCRIPTION

FIG. 1 is a right perspective view of an intake manifold with an integrated PCV port showing our new design;

FIG. 2 is a left perspective view of the design shown in FIG. 1;

FIG. 3 is a top plan view of the design shown in FIG. 1;

FIG. 4 is a bottom plan view of the design shown in FIG. 1;

FIG. 5 is a right side elevation view of the design shown in FIG. 1;

FIG. 6 is a left side elevation view of the design shown in FIG. 1;

FIG. 7 is a front elevation view of the design shown in FIG. 1; and,

FIG. 8 is a rear elevation view of the design shown in FIG. 1. The broken lines illustrate environmental structure and form no part of the claimed design.
